ATTACHÉ CASE

Lewis Lifton, New York, N. Y.

Application July 3, 1956, Serial No. 595,639

5 Claims. (Cl. 217—69)

2

corners of the lid and receptacle for strengthening such corners.

Fig. 1A is a sectional view on the line 1A—1A of Fig. 1.

Fig. 2 is a rear view of Fig. 1 on a smaller scale but with the hinged lid shown fully closed.

Fig. 3 is a fragmentary enlarged view of the receptacle shown in Fig. 1 prior to securing adjacent ends of the flexible covering to companion faces of a corner of the wooden frame of the receptacle.

10 Fig. 4 is a view similar to Fig. 3 but with the covering completely secured to a corner of the frame except for one end thereof.

Fig. 5 is a view along the lines of Fig. 4 however illustrating the ends of the covering appropriately secured to corner faces.

Fig. 6 is a front view of Fig. 5 but with a dihedral protective shield applied to the covered corner and with its wing carrier or shank in its unfolded position.

Fig. 7 is a view along the lines of Fig. 6 but showing the shank or wing carrier folded down and with the wing secured to the covering.

Fig. 8 is a vertical sectional view on the line 8—8 of Fig. 1, however showing the hinged lid closed and cooperating with the covered rim of the receptacle.

25 Fig. 9 is a sectional view on the bent line 9—9 of Fig. 7.

Fig. 10 is an inside perspective view of one dihedral protective shield shown in Fig. 1.

Fig. 11 is an enlarged horizontal sectional view on the line 11—11 of Fig. 2.

30 Fig. 12 is an enlarged perspective view of a corner of the lid showing the covering unwrapped from its wooden frame.

Fig. 13 is a view similar to Fig. 12 but showing one end of the covering glued to one vertical face of the corner and with the companion end of the covering exposing the adjacent vertical face of the corner.

35 Fig. 14 is a fragmentary view of Fig. 13 showing the both ends of the covering secured to the vertical faces of the corner and with the upper parts of these ends in overlapping relation and secured to horizontal shoulders of the lid.

Fig. 15 is a view similar to Fig. 14 but with a protective shield applied to the covered corner and with the wing carrying shank unfolded and unsecured to the corner.

40 Fig. 16 is a view along the lines of Fig. 15 illustrating the protective shield fastened to the sides of the covered corner and with the wing secured against the overlapped parts of the ends of the covering and fastened thereagainst, and

45 Fig. 17 is a view of a modified dihedral protective shield.

The attaché case is generally designated A and comprises a closed bottom receptacle C having an open top adapted to be closed by the swingable lid L. Spaced hinges H (Fig. 2) are effectively secured to the back walls 50 of the receptacle and lid to permit the latter to be swung relative to the receptacle. As shown, both the lid and receptacle are rectangular. Receptacle C comprises a wooden frame F while lid L includes the wooden frame FF. The ends and sides of frame F forming its corners are effectively secured together by the conventional and glued mortise and tenon joints 10 and 11 as shown in Fig. 3. Similar glued together mortise and tenon joints 12 and 13 shown in Fig. 12 appropriately connect and secure the sides and ends of frame FF to lid L to constitute 55 the corners of the latter.

Frame F has its upper part rabbeted to define rim R and aligned horizontal shoulders 14. Bottom wall 15 (Figs. 8 and 11) of receptacle C effectively closes the lower part of frame F. A leather covering 16 is glued 60 against the outer surface of bottom wall 15 (Fig. 8), the outside faces 17 of frame F, to the shoulders 14, and

The subject matter of this invention is concerned with corner strengtheners particularly applicable, although not necessarily, to an attaché case of the type usually comprising, a receptacle and a hinged lid together with controllable locking means to hold the lid closed, and an appropriate handle for conveniently carrying the case about. Usually an attaché case has a covering of leather, or of imitation or simulated leather. Such coverings are glued to the frames of the lid and receptacle and to upper and lower closure walls thereof. The sides of the covering at the corners of the lid and receptacle hitherto also included lips or flanges which were swung against the ends of the covering at these corners and subsequently stitched against such ends. It is a well known fact that during stitching the needle severing the covering produces a line of holes weakening such covering. Thus often in actual practice during handling and use of the attaché case, the seams formed by the lines of stitching at times became disabled, causing a flange or lip to open up thereby producing an unsightly appearance. When this occurred, the attaché case was generally sent back to the manufacturer for repair. New seams had to be restitched by hand in that the needle had to pass through the same holes previously made in the covering to avoid further weakening of the latter. Many times repair was impossible in that the old line of holes were in part worn or torn. The object of the invention resides in the provision of a novel attaché case wherein no lips or flanges at the sides of the covering for the lid and receptacle frames are required thereby eliminating the need of undesirable seams formed by lines of stitching. Another object comprehends the utilization of dihedral corner strengtheners to conceal companion corner faces of the coverings. Another object is realized in utilizing dihedral strengtheners to protect the corners of the attaché case substantially throughout their entire heights, thereby not only providing a stronger attaché case construction but one which adequately wears better apart from having a more desirable appearance. Another object is to provide a dihedral or corner strengthener having means to preclude accidental separation or opening of overlapped portions of the coverings at the corners of the lid and receptacle and concomitantly serving to effectively conceal such overlapped portions. Another object resides in the provision of compensatory means carried by dihedral strengthener to allow for uncontrollable variations in heights of either the receptacle or its swingable lid, nevertheless affording appropriate protection against misuse and shock substantially along the entire heights of the lid and receptacle. Other important objects and features will appear from the following detailed description taken with the accompanying drawings wherein:

Fig. 1 is a perspective view of the attaché case illustrating the lid partly broken away and swung from the receptacle of the case and further illustrating protective metal shields according to my invention secured to the

about the outer faces of the upstanding rim R and against the upper part of inside surface 18 of frame F. However, companion ends 20 and 21 of covering 16 are glued to the vertical faces constituting the corners thereof. Ends 20 and 21 of covering 16 at the corners have upper portions 22 and 23 glued to shoulders 14 and rim R and in overlapping relation and also glued against the inside surfaces 18 of the frame at the corners.

A metal one piece dihedral shield DP is effectively secured to each corner of receptacle C. Each protective shield comprises a dihedral column 25 having merged webs 26 characterizing approximately a right angle adapted to conveniently receive a covered corner of frame F. Webs 26 are each provided with upper and lower ears 27 and 28, each of which is provided with an opening 29 (Fig. 10). Integral with lower diverged ears 28 is the arcuate base or bottom wall 30 forming with these ears a socket for closely receiving and embracing the lower part of a corner. Nails 31 are inserted into openings 29 and are driven into the covered frame F to secure webs 26 firmly in place.

The height of a column 25 of each protective shield DP, that is, its distance from its base 30 to the upper faces 32 of ears 27 thereof is substantially coextensive with the height of the receptacle except for its rim R, that is, a distance between covered shoulders 14 of frame F and the covered bottom wall 15. Thus each corner shield DP protects the entire height of a corner and further includes means to conceal as well as prevent the overlapping portions 22 and 23 from accidentally opening up or separating. In this connection, it will be observed that integral with ears 27 and common thereto and extending upwardly therefrom at their juncture is a shank or pilot 33 carrying the flared wing or flange 34. Shank 33 in fact is a connection which is adapted to be bent or folded against the covered shoulders 14, that is, against the overlapped portions 22 and 23 of covering 16 (Fig. 9). A nail 35 which passes through opening 36 in wing 34 is driven through the overlapped and glued portions 22 and 23 and into frame F, hence holding down these overlapped ends against separation.

Shank or pilot 33 of course may be bent along any part of its length toward the covered shoulders 14 of a frame corner to adjust for uncontrollable height differentials of a column 25 or the height of a covered frame corner, that is, uncontrollable variations in height incidental to manufacturing tolerances between column 25 and the covered corner of frame F it embraces, it may be compensated for in that shank or pilot 33 may always be folded at the elevation of the covered shoulders 14 to compensate for involuntary height differentials existing.

Suitably glued to the bottom wall 15 (Figs. 8 and 11) and against the lower part of inside faces 18 of frame F is the liner 40 which may be of simulated leather while a band 41 likewise of a simulated leather is also secured to the inside faces of frame F and against the overlapped portions 22 and 23 of the covering secured to the inside faces 18.

Coming now to Figs. 12 to 16 inclusive, one corner of wooden frame FF of lid L is shown. In these views the position of the lid is actually shown reversed from the normal position exhibited in Fig. 1. A covering 50 is glued to the external surface of frame FF. This covering 50 may be of a suitable leather or simulated leather having abutting ends 51 and 52 glued to companion faces of corners of the lid frame FF while the upper portions 53 and 54 are glued in overlapping fashion against the aligned shoulders or faces 55 and 56 which in fact constitute the bottom surface of frame FF desirably closed by wall 57 (Figs. 1 and 8) concealed by covering 50 also secured thereto. Liner 58 (Figs. 1 and 8), preferably of simulated leather, is glued to the inside surface of cover or wall 57, to the inside surface of frame FF and against the overlapped portions 53 and 54.

Except for their heights, that is, their elevations, metal

dihedral shields or strengtheners LDP are structurally identical to the protective dihedral or corner shields or strengtheners DP. Strengtheners LDP are anchored to the outside corners of lid L. Since the corner strengtheners for both lid L and receptacle C of case A are substantially structurally identical, for the sake of simplicity corresponding portions of the strengtheners of both lid L and receptacle C are identified by like reference characters. Dihedral strengtheners LDP thus conceal the corners formed by ends 51 and 52 of covering 50 and wing 34 holds overlapped portions 53 and 54 against accidental opening.

The dihedral strengtheners or shields for both the lid and receptacle include shanks 33 adapted to be bent or folded at the elevation of the overlapped portions of their respective frame coverings to compensate for variations in heights of such frame, that is, in the event such heights are greater than the heights of respective dihedral columns 25. In all instances however nails 31 secure the columns 25 against the covered corners while nails 35 secure the wings 34 to the overlapped portions of the covering of the lid and of the receptacle C.

In Fig. 17 the dihedral strengthener or shield DP' is along the lines of the shield or strengthener DP shown in Fig. 10 except pilot or stem 33 and its wing 34 have been eliminated. Instead a top wall or roof 60 is provided. This top wall is integral with and is substantially normal to ears 27' of webs 26'. Shield or strengthener DP' therefore has a fixed height or elevation and incapable of adjustment as in the case of the strengthener shown in Fig. 10 by reason of the foldable pilot or shank 33. In use, a dihedral strengthener or shield DP' has its top wall 60 and base 30' embracing upper and lower covered surfaces at a corner of the receptacle and of the lid and thereafter webs 26' are fastened in a manner earlier explained to the faces of such corners.

For purposes of specification receptacle C and lid L each may be considered as an enclosure and attaché case A in fact is an article holding portable device. The expression "height" has been used to designate the depth of an enclosure, and may be used interchangeably with the term "elevation." A swingable handle 70 is carried by receptacle C. Swingable hasps 71 and complementary latch means 72 serve to removably lock lid L to receptacle C.

Various changes may be made in details of construction and arrangement of parts without departing from the scope of the invention or sacrificing any of the advantages thereof inherent therein.

I claim:

1. A dihedral strengthener adapted to be applied to substantially the entire elevation of companion faces of a corner of an article carrying enclosure having upper and lower surfaces at the upper and lower limits of said elevation; comprising, angularly arranged webs substantially coextensive with the extent of said elevation for embracing said companion faces, a base integral with the lower parts of said webs and defining therewith a socket for receiving the lower part of said corner and constituting a seat for said lower surface, wing means to conceal and engage a portion of said upper surface, a shank interconnecting said webs and wing means, means anchoring said webs to said faces, and means anchoring said wing means to said upper surface.

2. A metal one piece dihedral strengthener adapted to be applied to substantially the entire elevation of companion faces of a corner of an article carrying enclosure having upper and lower surfaces at the upper and lower limits of said elevation; comprising, angularly arranged webs substantially coextensive with the extent of said elevation for embracing said companion faces, a base integral with the lower parts of said webs and defining therewith a socket for receiving the lower part of said corner and constituting a seat for said lower surface, wing means spaced from said webs to conceal and engage a portion of

said upper surface, a bendable shank interposed between said webs and wing means and integral therewith, means for fixing said webs to said faces, and means for fixing said wing means to said upper surface.

3. A metal one piece dihedral strengthener adapted to be applied to substantially the entire elevation of companion faces of a corner of an article carrying enclosure having upper and lower surfaces at the upper and lower limits of said elevation; comprising, merged and angularly arranged webs substantially coextensive with the extent of said elevation for embracing said companion faces, a base integral with the lower parts of said webs and defining therewith a socket for receiving the lower part of said corner and constituting a seat for said lower surface, a pilot extending from said webs at the confluence thereof, and wing means carried by said pilot.

4. The dihedral strengthener according to claim 3 char-

acterized further in that said pilot is attenuated relative to said webs and wing means and adapted to be folded at said upper surface to compensate for uncontrollable variations in elevation of said corner.

5. The dihedral strengthener according to claim 4 wherein the wing means is at the upper part of and overhangs said pilot and flares outwardly therefrom and is adapted to be secured to overlapped portions of a covering for said enclosure to conceal said overlapped portions and to prevent opening thereof.
